(57) **CLAIM**

We claim the ornamental design for a insulated beverage container, as shown and described.

DESCRIPTION

FIG. 1 is a perspective front view of the insulated beverage container;

FIG. 2 is a first side view of the design embodiment shown in FIG. 1;

FIG. 3 is a second side view of the design embodiment shown in FIG. 1;

FIG. 4 is a third side view of the design embodiment shown in FIG. 1;

FIG. 5 is a top view of the design embodiment shown in FIG. 1; and,

FIG. 6 is a bottom view of the design embodiment shown in FIG. 1.

The ornamental design which is claimed is shown in solid lines in the drawings. The broken lines in the drawings are for illustrative purposes only and form no part of the claimed design.

1 Claim, 6 Drawing Sheets
